APPARATUS FOR DIE CASTING ARTICLES

Roy E. McIntosh, New York, N. Y., assignor to
Star Expansion Bolt Company, New York, N. Y.,
a corporation of Illinois

Application January 30, 1937, Serial No. 123,184

2 Claims. (Cl. 22—94)

This invention relates to an apparatus for die casting articles having internal threads therein.

More particularly stated, the invention relates to an apparatus for die casting and ejecting 5 from the die a group of articles, such as nuts, internally threaded caps, or internally threaded expanding elements for expansion anchors.

When such articles are to be cast, the mold has 10 positioned therein a threaded core pin and the metal is forced under pressure into the mold and around the pin. In the methods heretofore used, after the casting has set, the pin is threaded out of the article and the article is ejected by an ejector pin or other suitable means which is 15 usually moved through the core and forces the cast article from the die.

This invention has for its salient object to 20 provide a simple and practical apparatus for simultaneously withdrawing a core pin from the cast article and ejecting the article from the mold.

Another object of the invention is to provide 25 simple and practical means whereby the opening of a die casting mold or the removal of the die cover therefrom will automatically set in operation means whereby the core pin will be removed from the mold and the article will be ejected therefrom.

Further objects of the invention will appear 30 from the following specification taken in connection with the drawings which form a part of this application, and in which—

Fig. 1 is an elevational view of apparatus constructed in accordance with the invention and adapted for use in carrying out the method;

Fig. 2 is a sectional elevation through the die, the die being closed;

Fig. 3 is a view similar to Fig. 2 but illustrating the die with the cover removed and the die casting ejected;

Fig. 4 is an elevational view of the die mold; and

Fig. 5 is an elevational view of the die casting formed in the mold.

The invention briefly described consists of a method of die casting a plurality of threaded articles in a group and of simultaneously separating the core pins and articles and ejecting the casting from the mold after the casting has set. The invention further consists in apparatus for carrying out this method and in apparatus for simultaneously opening the die and ejecting the casting therefrom.

Further details of the invention will appear from the following description.

In the particular embodiment of the apparatus

illustrated in the drawings there is shown in Fig. 1 a machine comprising a base 10 on which is supported a die 11, the details of which are illustrated in Figs. 2 and 3, the die being closed by a cover 12. The molten metal for the die is 5 forced under pressure from a receptacle or pot 13 through a conduit 14 into the die mold 11.

The cover 12 is held in closed position by a plunger 15 having a piston 16 on one end disposed in a pneumatic cylinder 17.

The die mold 11 is constructed in the manner shown in Fig. 4, with a gate 20 through which the molten metal enters the mold. The gate 20 communicates with a groove 21 which forms a conduit for conducting the metal around the 15 mold and to laterally extending conduits which communicate with the die cavities 23 in which the cast articles are formed.

In each of the cavities 23 there is disposed a threaded core pin 24 and each core pin has a 20 rearwardly extending spindle 25 formed thereon, to which is secured a gear 26.

The gears 26 mesh with a centrally disposed gear 27 mounted on a shaft 28 supported in vertically extending portions 29 and 30 of the base 25 10. The front end of the shaft 28 is mounted in ball bearings 31.

A pulley 35 is rotatably mounted on the shaft 28 and is driven in any suitable manner, as by a belt 36. The pulley 35 forms a fly wheel and 30 has secured thereto a plurality of clutch pins 37 which are adapted to seat in sockets 38 of a shiftable clutch member or yoke 39 which is keyed to the shaft 28. When the clutch member 39 is shifted to the left viewing Fig. 1 the pins 37 will 35 enter the recesses 38 and the shaft will be driven by the fly wheel 35.

The clutch yoke 39 is engaged by a clutch shifting lever 40 pivoted on a fixed pivot 41 and having its lower end connected by a link 42 to 40 a lever 43. Lever 43 has a fork 44 at its lower end in which is positioned a fixed pin 45. The upper end of the lever 43 is pivoted at 46 to the die cover or closure 12.

In order to facilitate the stopping of the shaft 45 28 when the clutch is thrown out, a brake 50 of any suitable construction is mounted on the base 10 and frictionally engages a pulley 51 mounted on the left hand end of the shaft 28 viewing Fig. 1.

50

Operation

When the casting is to be formed the parts are disposed in the position illustrated in Figs. 1 and 2, with the die cover 12 closed and held in closed

position by the plunger 15. The metal is then forced into the mold under pressure and thereafter the plunger 15 is moved to the right opening the die mold and at the same time shifting the clutch yoke 39 to the left, connecting the fly wheel 35 to the shaft 28. The fly wheel is rotated in such a direction that the gears 26 will be rotated in a direction to cause the rotation of the threaded core pins 24 to eject the castings from the molds or cavities 23. Thus, the core pins and castings will be separated and at the same time the die casing will be ejected from the die.

Although one specific embodiment of the invention and one particular form of apparatus has been illustrated, it will be understood that changes in the construction and in the arrangement of the various parts may be made and that the method may be carried out by modified forms 20 of apparatus without departing from the spirit or scope of the invention, as expressed in the following claims.

What I claim is:

1. Apparatus of the character described com-

prising a stationary die having a plurality of mold cavities, means for closing the die, rotatable threaded core pins in the mold cavities in said stationary die, means for rotating said pins in a direction to eject the cast articles from the mold cavities of the stationary die, means for moving said die closing means to open and closed positions, and means connected to said moving means for setting said pin rotating means in operation when the die is opened.

2. Apparatus of the character described comprising a stationary die, a closure for the die, rotatable threaded core pins in the die cavities of the die, a power shaft for rotating said pins in a direction to eject the casting from the die cavities of the stationary die, a clutch between the shaft and pins, means for opening and closing the die closure and operative connections between said closing means and said clutch so arranged that the clutch will be thrown in when the closure 20 operating means is actuated to open the die.

ROY E. McINTOSH.
